US00D909160S

(12) **United States Design Patent** (10) **Patent No.:** **US D909,160 S**
(45) **Date of Patent:** **** Feb. 2, 2021**

(54) **RATCHET WITH ONE PAWL**

(71) Applicant: **Wright Tool Company**, Barberton, OH (US)

(72) Inventors: **Kenneth R. Milligan**, Uniontown, OH (US); **Terry G. Taylor**, Copley, OH (US)

(73) Assignee: **Wright Tool Company**, Barberton, OH (US)

(**) Term: **15 Years**

(21) Appl. No.: **29/676,683**

(22) Filed: **Jan. 14, 2019**

(51) LOC (13) Cl. **08-05**

(52) U.S. Cl.

USPC **D8/25; D8/21**

(58) **Field of Classification Search**

USPC D8/21-29, 29.1, 114, 499, 321, 81, 52, D8/61, 107, 57, 346, 334, 333, 72-75, D8/393-395, 63, 93, 14, 330, 336, 400, D8/349, 467, 356, 692, 693, 17, 367, 368, D8/369, 370, 371; 81/119, 177.1, 177.2, 81/57.5, 478, 177.7, 177.8, 166; D15/148, 140, 138, 5

(57) **CLAIM**

The ornamental design for a ratchet with one pawl, as shown and described.

DESCRIPTION

FIG. 1 is a rear perspective view of the design; FIG. 2 is a front perspective view of the design as shown in FIG. 1;

FIG. 3 is a rear view of the design as shown in FIG. 1; FIG. 4 is a front view of the design as shown in FIG. 1; FIG. 5 is a side view of the design as shown in FIG. 1; FIG. 6 is a side view of the design as shown in FIG. 1, shown from the opposing side view as that shown in FIG. 5; FIG. 7 is a top view of the design as shown in FIG. 1; and, FIG. 8 is a bottom view of the design as shown in FIG. 1. The broken line shown are included for the purpose of illustrating portions of the ratchet with one pawl and forms no part of the claimed design.

1 Claim, 3 Drawing Sheets
